UNITED STATES PATENT OFFICE.

MADISON G. HAWKE, OF SARATOGA SPRINGS, NEW YORK.

THILL-COUPING.

SPECIFICATION forming part of Letters Patent No. 423,763, dated March 18, 1890.

Application filed February 1, 1890. Serial No. 338,900. (No model.)

To all whom it may concern:

Be it known that I, MADISON G. HAWKE, a citizen of the United States, residing at Saratoga Springs, in the county of Saratoga and State of New York, have invented certain new and useful Improvements in Thill-Couplings; and I do hereby declare the following to be a full, clear, and exact description of the invention, such as will enable others skilled in the art to which it appertains to make and use the same.

My invention relates to improvements in thill-couplings, and is designed as an improvement on the Letters Patent granted to me January 7, 1890, No. 419,016. The invention disclosed in said Letters Patent consists, essentially, in a box having a semi-cylindrical casing forming the bottom thereof, and stationary circular disks, to which said casing is secured, in combination with disks pivoted to the stationary disks and having a semi-cylindrical casing provided with a slot to receive the shaft-iron.

The object of the present invention is to provide means for automatically locking the pivoted disks and their casing when in a closed position, thereby securely holding the shafts in place.

The invention consists in the several novel features of construction and new combinations of parts hereinafter fully described, and then definitely pointed out in the claims.

In the accompanying drawings, illustrating the invention, in which similar reference-numerals indicate corresponding parts in all the figures, Figure 1 is a perspective view of a thill-coupling constructed according to my invention applied to a carriage or wagon axle. Fig. 2 is a sectional view of the same. Fig. 3 is a plan view of the coupling with the shaft-iron removed. Fig. 4 is a front view of the same. Fig. 5 is a perspective view of the tool for unlocking the coupling.

In the said drawings, the reference-numeral 1 designates an ordinary wagon or carriage axle.

2 designates the box for the reception of the cylindrical block 3, secured to the shaft-iron 4. This box consists of two circular disks 5, connected together by the semi-cy-

lindrical sheet or plate 6, connected to the lower half of the peripheries of said disks. This box is secured to the clip 7, which may be of any ordinary construction capable of being secured to the axle.

To each of the disks 5 are pivoted the disks 10, having secured thereto or formed therewith a semicircular wall or casing 11, provided at one edge with a slot 12. The disks can revolve freely on their pivots, so as to cover and uncover the top of box 2, as desired.

Centrally secured upon the inner side of box 2, near the top thereof, is a semi-cylindrical spring 13, which extends around said box and its free end is formed with or bent into a projecting flange or lip 14, which passes through a slot 15 in said box. It will be seen that as the casing 11 is revolved upon its pivots in the disks 12 the flange or lip 14 will engage with the rear or bottom side thereof and prevent any movement backward, thus securely locking the shafts. In this condition the shaft-irons cannot be removed until the said flanged end of the spring is pushed in and the casing 11 thus allowed to move back. For the purpose of pushing in the said spring to allow the casing 11 to rotate, I provide the box 2, on the outside thereof, in proximity to the slot 15, with an arm 16, to pass through an aperture 17 in the head 18 of an unlocking-lever 19. This head 18 has a concaved face and shoulders 20 on each side thereof, and is used by passing the arm 16 through aperture 17. Then by manipulating said lever one of the shoulders 20 will press upon the flange or lip of the spring projecting through box 2 and force the same in and allow the casing 11 to be rotated.

The numeral 4 designates the shaft-irons, having cylindrical block or head 3, which fits snugly in box 2.

Having thus described my invention, what I claim is—

1. The combination, with the box having a semi-cylindrical casing provided with a slot and forming the bottom thereof and stationary circular disks, to which said casing is secured, of the disks pivoted to said stationary disks, having a semi-cylindrical casing provided with a slot to receive the shaft-iron,

and a semicircular spring secured in said box, having a flanged end projecting through the slot therein, substantially as described.

2. The combination, with the box having a 5 semi-cylindrical casing provided with a slot and forming the bottom thereof and stationary circular disks, to which said casing is secured, of the disks pivoted to said stationary disks, having a semi-cylindrical casing provided with a slot to receive the shaft-iron, 10 a semicircular spring secured in said box,

having a flanged end projecting through the slot therein, and an arm secured to the outside of said box to receive a tool for depressing said spring, substantially as described. 15

In testimony whereof I affix my signature in presence of two witnesses.

MADISON G. HAWKE.

Witnesses:

EDWARD H. HAWKE,
WM. HAY BOCKES.
